THERMOMETER RACK

Arthur J. Langdon, East Hampton, Conn., assignor to
Edward Weck & Company, Inc., Long Island, N.Y., a
corporation of Delaware

Filed June 9, 1965, Ser. No. 85,648

Term of patent 14 years

(Cl. D83—1)

FIG. 1

FIG. 2

FIG. 3

FIG. 1 is a perspective view of a thermometer rack showing my new design;

FIG. 2 is a side elevational view thereof;

FIG. 3 is a top plan view thereof.

The broken line representation of envelopes containing thermometers in FIGS. 1, 2 and 3 are for purposes of illustration only.

I claim:

The ornamental design for a thermometer rack, substantially as shown and described.
